UNITED STATES PATENT OFFICE.

NOEL E. POWERS, OF LANSINGBURG, ASSIGNOR TO WILBUR, MILLER & WILBUR, OF TROY, NEW YORK.

CAPE-COLLAR.

SPECIFICATION forming part of Letters Patent No. 408,848, dated August 13, 1889.

Application filed April 11, 1889. Serial No. 306,788. (No model.)

To all whom it may concern:

Be it known that I, NOEL E. POWERS, a resident of Lansingburg, in the county of Rensselaer and State of New York, have invented 5 certain new and useful Improvements in Cape-Collars; and I do hereby declare that the following is a full, clear, and exact description of the invention, that will enable others skilled in the art to which it appertains to make and 10 use the same, reference being had to the accompanying drawings, and to the letters of reference marked thereon, which form a part of this specification.

Similar letters refer to similar parts in the 15 several figures therein.

My invention relates to improvements in cape-collars; and it consists of the novel construction and combination of parts herein-after described, and pointed out in the claim.

20 Figure 1 of the drawings is a top plan view of the cape detached from the collar proper and laid out flat. Fig. 2 is a similar view of the cape attached to the collar proper. Fig. 3 represents a side elevation, upon an enlarged 25 scale, of the completed collar, showing the relative position of its parts while in use upon the neck of the wearer. Fig. 4 is a plan view showing the outer or face side of the collar proper as it would appear when laid out flat 30 before the cape is attached. Fig. 5 is a cross-section of the detached cape, taken on the broken line $x x$ in Fig. 1. Fig. 6 is a cross-section of the collar completed, taken on the 35 broken line $x x$ in Fig. 2. Fig. 7 is a cross-section of the unfinished collar proper, taken on the broken line $x x$ in Fig. 4.

The cross-sectional views are somewhat exaggerated in form and size for convenience in illustration.

40 The collar proper may be of any known form of lady's collar, made up of two or more plies of fabric, but having one ply wider than the collar proper, so that it projects below the lower edge of such collar.

45 As generally constructed, the capes of cape-collars are made of a single ply of fabric, a large part of which is worn in contact with the person, for the reason that ladies' under-garments are frequently or generally cut low-necked and without neck-bands.

The capes serve to retain the collar in proper position upon the neck, and are made to flare or project angularly to the collar proper to better fit the form of the wearer. It is very desirable to re-enforce the cape-ply along the 55 edge by which it is united to the collar proper to increase its strength and durability; also, to cover the seam by which the cape is joined to the collar proper to prevent its chafing and irritating the neck of the wearer. I am able 60 to cover this seam, and at the same time employ the seam-cover to re-enforce the cape, by extending one of the plies of the collar proper down below its lower edge and spring-stitching the same onto the cape-body. The capes 65 of cape-collars are made to flare or project angularly to the collar proper by giving the inner edge of the capes a curved or concave form and securing that edge to a comparatively straight edge on the lower part of the 70 collar proper. The angle of projection depends upon the degree of curvature of the curved edge. The sharper the curve the nearer will the angle of projection approach that of a right angle.

75 A is the cape, which may have a binding-strip A' around its outer edge. Its inner edge is cut to form a sharp curve described by the circular line A². The collar proper B is shown formed of three plies B', B², and B³. The 80 plies B' and B³ are turned in at their upper edge and all three plies secured together by a line of stitching B⁷. The ply B' is made wider than the other plies to form an extended or cape-lapping portion B⁴, which is 85 provided with a plurality of notches B⁵ and has its projecting or cape-lapping edges finish-folded, as shown at B⁶. The inner curved edge of the cape is then inserted between the lower folded-in edges of ply B³ and ply B', as 90 shown in Fig. 6, and secured therein by the line of stitching B⁸. The cape-lapping ply B⁴, the lower edge of which is approximately straight, is then spring-stitched, as hereinafter more fully explained, to the body part of 95 the cape by the line of stitching B⁹, and when desired the several plies of the body part may be additionally secured by a line of stitching B¹⁰. The circular broken line C in Fig. 1 represents approximately the lower or 100

outer boundary line of the part of the cape which is inserted between the plies of the collar proper. The broken lines C' represent the outlines of the finish-folded edges of the 5 notched cape-lapping ply of the collar proper as the same appears after being spring-stitched to the body of the cape upon its under side by the line of stitching B⁹.

The foregoing general description is sufficient to enable any one skilled in the art to make my improved collar when it is understood what I mean by the term "spring-stitched." I apply such term to a straight-edge lapping ply, and mean that such a ply is 15 stitched along its lapping edges by a curved line of stitching upon a lapped curved-edge ply in such a manner that the straight and curved edges of the lapping plies are made substantially parallel with the curved line of 20 stitching and with each other.

It will be observed from an inspection of Fig. 2 that the cape-lapping edge represented by the broken line C' of the extended ply of the collar proper, which was straight, as shown 25 in Fig. 4, is curved and parallel to the lower edge of the collar proper, and therefore to the inner curved edge of the cape; also, that the arcs of circles represented by the broken lines C' have a larger radius than the arc of 30 a circle described by the outline of the collar proper, as seen in Fig. 2, and that the inner edge of the cape as cut from the fabric and shown in Fig. 1 has a sharper curve than it has after it has been secured to the collar 35 proper and after the finish-folded edge B⁶, which was straight, has been stitched upon it, as shown in Fig. 2.

As the straight finish-folded cape-lapping edge is guided by the sewing-machine operator to insert the curved line of stitching B⁹ 40 substantially parallel with the inner curved edge of the cape, the cape-lapping edge is slightly stretched or sprung and the cape-body slightly fulled, so that the resulting 45 curves in the lines of stitching and parallel edges are less sharp than the curve described by the inner edge of the detached cape when laid out flat, as shown in Fig. 1. The cape being made of a single ply of flexible yielding material, the parts assume a smooth appearance when laundered or pressed, a large 50 degree of the curvature of the cape-edge being imparted to the once-straight cape-lapping edges. It would be impracticable to 55 spring-stitch the cape-lapping edge the whole length of the collar without two or more slits or notches B⁵ therein, as the fabric could not conveniently be given the necessary spring to produce a smooth surface; but the insertion 60 of a plurality of notches divides the lapping portion of the ply into comparatively short sections, which can be separately and quickly spring-stitched to the cape.

A cape-collar so made will, when unconstrained, occupy about the position shown in Fig. 2, the curved edge of the cape, the cape-lapping edge, and the curved line of stitch-

ing being all substantially parallel with each other, and the cape projecting almost right-angularly from the collar proper, as shown in 70 Fig. 6; but when the ends of the collar are brought together, as in use, and as shown in Fig. 3 and indicated by the broken line C³ in Fig. 2, the outer edge of the cape is forced downward in the rear to about the angle represented by the line C⁴ and in front to about the angle represented by the line C⁵ in Fig. 3, the manner and causes of which change in position are well known and understood by those skilled 80 in the art of making cape-collars. Such a shape causes the cape when in use to fit the form of the wearer and affords a comfortable means of securing the collar upon her neck. By re-enforcing the cape at its junction with the collar proper and for a considerable distance into the body of the cape I not only 85 strengthen the cape, so that it is not so likely to be ripped from the collar proper, but the reinforced part does not easily ruffle up in use and present sharper edges to irritate the person of the wearer. By extending a ply of the 90 collar proper to effect such re-enforcement I am able at the same time to cover the seam which unites the cape and collar proper, thereby presenting a smooth comfortable surface 95 at every point on the collar. I am able to accomplish these results with very little expense, as the extended ply of the collar proper can as easily be finish-folded for 100 stitching upon the cape-body as upon the edges of the cape and other collar plies in the manner heretofore practiced. Very little additional labor is required to notch the cape-lapping edge, as only two or three notches 105 are required when the straight-edge cape-lapping ply is spring-stitched to the cape-body, as I have described.

When I employ the term "straight-edge" lapping ply I do not wish to be understood as limiting the form of the ply to one having 110 its edge absolutely straight, as any of the well-known forms of ply used in the manufacture of ladies' collars may be employed.

The plies may be slightly curved, as shown by the curved broken lines C⁶ in Fig. 4.

When desired, the cape may be made of 115 several pieces, as indicated by the broken lines C² in Fig. 1.

I do not wish to be limited by the term "finish-folded" to any particular method of 120 finishing the edge. Any known method may be employed, or the edge may be left unfinished as it is cut from the fabric, when desired.

I do not wish to be limited to any particular 125 form of notch B⁵, the essential feature being the division of the cape-lapping ply into sections by reducing the width of such ply between the sections. On the 17th day of June, 1889, an application for United States Letters Patent covering the method of making 130 the cape-collar herein shown and described was filed by me and given the Serial No. 314,554.

What I claim as new, and desire to secure by Letters Patent, is—

A cape-collar consisting of the collar proper formed of a plurality of approximately 5 straight-edge plies, one of which plies extends below the bottom edge of such collar proper, and the cape formed of a ply of fabric having its inner edge concaved or curved, all of said plies being fastened together by a line 10 of stitching along the lower straight edge of the collar proper and the inner curved edge

of the cape, the extended collar-ply lapping the cape and having its lapping portion notched and secured to the cape-body by a line of stitching along the edge of the lapping 15 ply, substantially as described.

In testimony whereof I have hereunto set my hand this 9th day of April, 1889.

NOEL E. POWERS.
